[57] ABSTRACT

Apparatus for cleaning small parts such as assembled watches, or watch parts in a basket, wherein supporting structure may be adjusted for vibratory or elliptical motion when cleaning assembled watches or circular motion when cleaning parts in a basket. The supporting structure involves a motor driven plate rotatable about its central axis, and a work supporting plate carried thereby and adjustable between a concentric position and an eccentric position.

APPARATUS FOR CLEANING SMALL PARTS

This invention relates to an apparatus for the cleaning of small parts, such as dismantled or non-dismantled works of clocks, by movement of the parts placed on a parts holder in a cleaning fluid, whereby the parts are moved selectively by rotation or by vibration.

The parts holder is driven by an electric motor. Such an apparatus aims at the cleaning of such parts by the bringing about of a relative movement between these parts and the cleaning fluid. The parts may therefore be affixed as complete clock works, on a parts holder which is then moved relatively to the cleaning fluid, or a basket may also be provided in which the individual parts are then disposed.

In the cleaning of dismantled works of clocks, it is advantageous to move these in the cleaning bath in a clear circular movement of rotation. With undismantled works of clocks on the other hand, the cleaning action is increased if the complete works are moved in a vibrating manner in the cleaning fluid.

In a known apparatus the parts holders had to be exchanged if it was desired to change over from rotation to vibration or vice-versa. The invention aims at a simplification of this changing over.

This problem is solved according to the invention, with an apparatus of the aforementioned kind by means of a coupling between the parts holder and the motor shaft with which the parts holder is adjustable concentrically or eccentrically to the motor shaft.

In doing so, it is advantageous for the adjustment of the parts holder in respect of the motor shaft, for a screw to be provided.

One suitable embodiment of the invention consists in that on the motor shaft, at least one plate is fixed which rotates concentrically or eccentrically and to which the parts holder is exchangeably fixed.

According to whether the plate or plates rotate concentrically or eccentrically the parts to be cleaned, which therefore in their turn are firmly connected to the parts holder, carry out a circular movement of rotation or an elliptical movement of rotation. These elliptical movements of rotation correspond to a movement of vibration. The parts holder may be basket in which the dismantled individual parts are placed. It may be a workpiece holder which carries non-dismantled works of watches for example, of pocket watches or the works of alarm clocks.

Advantageously, there is fixed on the motor shaft, an upper plate and a lower plate which are pivotable towards one another about a common pivot, which runs parallel at a distance from the axis of rotation. The axis of rotation of the upper plate may thereby coincide with the middle axis of the circular cylindrically constructed upper plate, whilst the likewise circular cylindrically constructed lower plate can be pivoted from this position so that it runs eccentrically and produces in this position, the elliptical oscillations. If the lower plate, like the upper plate, rotates concentrically, the apparatus carries out a circular movement. With this arrangement, the upper plate has, with advantage, an arcuate elongated hole through which a fixing screw parallel to the axis of rotation penetrates, which is screwed to the lower plate located directly under the upper plate. This fixing screw may therefore fix the lower plate in respect of the upper plate in the circular or in the elliptical path of rotation.

According to a preferred embodiment of the subject matter of the invention, the lower plate has centrally downwards a continuation for receiving at least one bearing plate, rotatable relative to the lower plate, to which bearing plate, the parts holder is screwed. With this construction, the bearing plate, with its parts holder, rotates more slowly than the motor shaft because of the friction with the cleaning fluid, whereby a plurality of elliptical oscillation revolutions takes place.

Advantageously, two bearing plates are provided, one above the other, which run in a ball bearing on the projection of the lower plate. The lower plate may be provided centrally with a nut thread for receiving the parts holder.

The parts holder has centrally, a bolt thread, fitting in the nut thread, so that both parts can be screwed to one another.

In one simple particular construction, the common pivot of the lower plate and of the upper plate is formed by a screw which connects both plates rotatably to one another.

The invention will be described in more detail with reference to the accompanying drawings;

FIG. 1 shows a perspective view of the whole cleaning apparatus;

10 FIG. 2 shows a view of the rotary and vibratory unit with works of a watch suspended underneath thereon;

FIG. 3 shows likewise a perspective view of this unit with wire basket screwed thereon;

15 FIG. 4 shows a longitudinal section through the rotary and vibratory unit with the parts holder removed;

FIG. 5 shows a plan of the upper plate according to FIG. 4, wherein in the central position for the cleaning of the dismantled works is taken up, and

20 FIG. 6 shows a view corresponding to FIG. 5 wherein however, the lower plate is displaced in respect of the upper plate so that the eccentric position for the vibration cleaning of dismantled works is taken up.

In FIG. 1 there is illustrated a lower frame 1 with a time switch 2. On the lower frame there are located containers 3

25 made of glass or other transparent plastic, which serve for receiving cleaning fluid. A motor 4 is fixed to a cover plate 5 such that by moving (raising, rotating and again lowering) the cover plate in the direction of the arrow 6, after release of the fixing screw 7, the motor 4 can be placed over each of these glasses. By means of the shaft 8, it is possible upon raising the motor 4 in the direction of the arrow 6 to immerse or remove the rotary and vibratory unit 9 with the workpiece holder 10 fixed thereon in the cleaning fluid.

30 35 The rotary and vibratory unit 9 is shown separately in FIGS. 2 and 3. In FIG. 2 a workpiece holder with non-dismantled watch works 11 is shown. In FIG. 3 a wire basket 14 for dismantled or loose individual parts is illustrated. The wire basket 14 carries out a purely rotational movement whilst the workpiece holder 10 carries out a vibratory movement.

40 45 By simple adjustment of the screw 15 or by the rotation of the lower part 17 shown in FIGS. 4 to 6, the switching over from rotation to vibration takes place. In FIG. 4 is illustrated the rotary and vibratory unit 9 which is formed by an upper plate 16 and a lower plate 17. The screw 15 firmly connects these parts when it is tightened. If it is loosened the lower plate

dismantled watch works such as, for example, those of travelling alarm clocks.

I claim:

1. Apparatus for cleaning small parts as dismantled or non-dismantled watch-works, comprising a holder for works to be cleaned, drive means, means for supporting said works holder in drive connection to said drive means, said works holder supporting means including an adjustable coupling means for laterally altering the axial relationship between said drive means and said works holder to selectively impart to said works holder, a rotary or vibratory motion.

2. Apparatus for cleaning of small parts, in accordance with claim 1, characterized by means for locking said adjustable coupling following adjustment thereof.

3. Apparatus for cleaning of small parts, in accordance with claim 1, characterized by said coupling including a plate affixed to said drive means, a second plate adjustably connected to said first plate, said second plate having means for supporting said works holder.

4. Apparatus for cleaning of small parts, in accordance with claim 3, characterized by means pivotally connecting said second plate to said first plate at a location offset axially from

the connection of said first plate to said drive means, to permit altering of the axial relationship between said drive means and said works holder, and means for locking said second plate in a desired adjusted position.

5. Apparatus for cleaning of small parts, in accordance with claim 4, characterized by said locking means including an arcuate slot in one of said plates and a tightening screw through said slot and threadedly engaging in the other of said plates.

6. Apparatus for cleaning of small parts, in accordance with claim 3, characterized by said means for supporting said works holder as including a third plate rotatably carried by said second plate, said third plate having means for removable attachment thereto of said works holder.

7. Apparatus for cleaning of small parts, in accordance with claim 6, characterized by said means for removable attachment of said works holder to said third plate, including a threaded recess in said third plate, axially located with respect to said second plate.

8. Apparatus for cleaning of small parts, in accordance with claim 6, characterized by a ball bearing mounting between said second plate and said third plate.
